DESIGN FOR A PAPER HOLDER EQUIPPED TOILET BOWL

David Vigo, Ann Arbor, Mich.

Application May 23, 1940, Serial No. 92,545

Term of patent 3½ years

To all whom it may concern:

Be it known that I, David Vigo, a citizen of the United States, residing at Ann Arbor, in the county of Washtenaw and State of Michigan, have invented a new, original, and ornamental Design for a Paper Holder Equipped Toilet Bowl, of which the following is a specification, reference being had to the accompanying drawing, forming part thereof.

I claim:

The ornamental design for a paper holder equipped toilet bowl, as shown.

DAVID VIGO.
